JOHN TAYLOR, OF CONNELLSVILLE, PENNSYLVANIA.

Letters Patent No. 86,256, dated January 26, 1869.

IMPROVED MACHINE FOR WASHING AND SCOURING SAND AND OTHER SUBSTANCES.

The Schedule referred to in these Letters Patent and making part of the same.

To all whom it may concern:

Be it known that I, JOHN TAYLOR, of Connellsville, in the county of Fayette, and State of Pennsylvania, have invented a new and useful Machine for Scouring, Washing, and Conveying Sand to a platform, or into cars, without manual labor; and I do hereby declare that the following is a full and exact description thereof, reference being had to the accompanying drawing, making a part of this specification, in which—

Figure 1 is a perspective view of my machine;

Figure 2 is a sectional elevation, as formed by a plane passing longitudinally along the first washing-trough, as presently to be described;

Figure 3 shows, in perspective, the construction of the stem, wheels, and buckets, which operate in each washing-trough; and

Figure 4 is a full and somewhat enlarged view of one of the buckets.

Like letters of reference indicate like parts in each.

The nature of my invention consists, first, in the construction of a sand-washing and scouring machine, having one or more troughs inclined in a direction the opposite of that in which the sand is to be carried, and in each trough, a reciprocating stem, mounted on wheels or otherwise, so as to operate with small loss by friction, on the under side of which stem or stems are attached buckets, which operate close to the sides and bottom of the trough or troughs, and which are attached to the stem in such way that, in reciprocating back and forth in their respective troughs, they shall carry the sand upward but not backward; and

It consists, furthermore, in the combination of such devices with each other, and with a grinding-roller operating in a concave, whereby, in connection with the action of a stream or flow of water, the sand is thoroughly scoured, washed, and discharged from the machine in a suitable condition for use in the arts.

In the manufacture of glass and glass-ware, and for some other purposes, sand is required, as free as possible from all the impurities which are to be found in it as it is dug or quarried. Such impurities, or many of them, can be best removed by washing the sand in a stream of water, which mode of cleansing can be materially aided by bringing the grains of sand into intimate frictional contact, thereby more perfectly releasing from union with the sand, the soluble impurities, which impurities the water takes up and carries away.

To enable others skilled in the art to make and use my invention, I will proceed to describe its construction and mode of operation.

a is a trough, with close sides and bottom, and with the latter inclined somewhat in a direction the opposite of that in which the sand is to be carried.

This, with the other devices, is set in any suitable frame, *A*.

The inner sides of this trough are grooved or shouldered, as at *a'*, to afford a track for the wheels *b'*.

These wheels, *b'*, by their axles *b*, carry a stem, *b*, which is made so as to operate, by a reciprocating motion, back and forth lengthwise of the trough *a*.

By a hinge or other suitable joint, such as is shown at *c*, I attach to the stem *b*, and at suitable distances from each other, a series of buckets, *d*, which, when in operation, will work almost in contact with the sides and bottom of the trough.

The joint *c* is such that the buckets *d* may swing freely forward, that is, toward the higher end of the trough, but not backward; or, to secure the same end, I insert braces or stays, *e*, in the lower face of the stem *b*, and one just back of each bucket *d*, and in such relation thereto that such brace *e* will prevent the backward swing or movement of the bucket immediately in front.

A reciprocating motion is imparted to the stem *b* by a crank, *B*, rocking shaft, *B'*, and suitable connecting-rods, as shown, or by other apparatus ordinarily used for similar purposes. Sand is then fed into the trough *a*, a stream, jet, or flow of water passed in, and the stem *b* put in motion. With its forward or upward stroke, the buckets *d* being supported by braces *e* from behind, as described, will carry up all sand in front of them. With their backward stroke, they will swing forward, pass back over any sand that may be in the rear of them, and again move up, each bucket taking a new load.

The water, in the mean time, dissolves the soluble and washes away the lighter insoluble impurities that may be in the sand, and carries them off by a sluice, or gate, at the lower end of the trough *a*, not shown in the drawing.

The upper bucket of the series discharges the sand into a concave trough, *f*, in which operates a revolving cylinder, *f*, the working-faces of the two being so close together that the sand fed therein is subjected to a grinding-process, or, in other words, the grains of sand are brought into such intimate frictional contact that thereby the impurities will be still further loosened from their union with the sand, and by a stream of water fed in at the same time, will be taken up or washed away, as already described.

The cylinder and concave are so set as to incline toward the spout *g*, where the sand and water are discharged into a cistern, *g'*. The excess of water flows off through the spout *h*, and fresh water is fed in.

In the troughs *l l'*, which may be either inclined or horizontal, or a part inclined and a part horizontal, I arrange another stem or stems, *m m'*, with wheels, buckets, braces, &c., as before, and operating in the same way.

As the sand is carried forward and upward, in the trough *m*, the impurities are carried away by a stream or flow of water, fed therein at any desirable point, the excess of water being carried off at a spout, *h*.

The sand is carried along a horizontal trough, *l*, any

desirable distance, and discharged through trap-doors in the bottom closed by the slides *o*, or carried over the further end, on to a platform or car, as may be most convenient for use or shipment.

The stems *m m'* receive a vibratory or reciprocating motion by a crank-shaft, *p*, which connects with the rocking shaft *B*.

In making the machine described, any suitable material or materials may be used. The cylinder and concave are preferably made of cast-iron. Motion may be imparted to them by a pinion on the end of its axle meshing into the gear-wheel *s*.

What I claim as my invention, and desire to secure by Letters Patent, is—

1. In a sand-washing machine, a series of recipro-

cating buckets, operating in a trough or troughs, and attached to a stem or stems in such way as to carry the sand forward but not backward, while the latter is being cleansed of its impurities by a stream or flow of water, fed into the trough or troughs, substantially as set forth.

2. The grinding-roller *f* operating in a concave, *f'*, for scouring sand, when used in combination with stems, buckets, and troughs, substantially as and for the purposes hereinbefore set forth.

JOHN TAYLOR.
